COMBINED TRAILER AND WIRE STRINGER

Gerald A. M. Petersen, Santa Clara, Calif.

Application May 3, 1956, Serial No. 41,327

Term of patent 14 years

(Cl. D14—3)

FIG. 1

FIG. 2

Fig. 1 is a side view of a combined trailer and wire stringer, showing my new design therefor.

Fig. 2 is an end view of Fig. 1 as seen from the left in Fig. 1; and

Fig. 3 is a perspective view.

I claim:

The ornamental design for a combined trailer and wire stringer, as shown.
